UNITED STATES PATENT OFFICE.

MORRIS M. GRUBER, OF NEW YORK, N. Y., ASSIGNOR TO SONORA PHONOGRAPH COMPANY, INC., A CORPORATION OF NEW YORK.

SOUND-REPRODUCING APPARATUS.

Application filed May 4, 1925. Serial No. 27,714.

The recent rapid development of high powered sending and receiving apparatus for radio-telephony has necessitated quite radical changes in the form of the receiver and the methods for the proper adjustment of the parts in order to take care of the increased flux in the magnet system so as to preserve clarity and volume of sound reception. It is to accomplish these results that my present invention was designed, and one of the objects of this invention is to provide an improved, simple and effective means for magnifying the vibration of a diaphragm within an appropriate sound chamber under proper acoustic conditions to mechanically and electrically reproduce speech or sound waves electrically conveyed to the instrument, delivered in a magnified or amplified volume.

This invention relates to sound reproducing instruments and more particularly to the telephonic receiving type used for announcing and commonly known as a loud speaking receiver.

One of the objects of this invention is to provide a new and improved device of this type of few and simple parts, rigid and compact construction, and improved operation.

Another object of my invention is to provide a telephonic receiver having a permanent magnet, each pole of which is so machined to form two poles of like polarity having a coil located between them to produce the opposite effect in the poles on both sides of the armature causing it to actuate a diaphragm. In other words the magnetic effect first pulls the armature in one direction and due to the coil the magnetic forces are reversed and the armature is pulled back again.

With these and other objects in view, to be more fully set forth hereinafter, the invention consists in the novel construction, combination of elements, and arrangement of parts which will be exemplified in the operation and construction hereinafter described in the following specification and illustrated in the accompanying drawings, considered together or separately.

The inventive idea involved is capable of receiving a variety of mechanical expressions, some of which, for the purposes of illustration, are shown in the accompanying drawings.

The invention will first be described in connection with the accompanying drawings, illustrating one embodiment of the invention, wherein similar reference characters are used to designate corresponding parts throughout the several views, and then more specifically defined and indicated in the appended claims.

In the drawings illustrating this invention—

Fig. 1 is a longitudinal sectional view.

Fig. 2 is a view taken on the line 2—2 Fig. 1.

Fig. 3 is a view taken on the line 3—3 Fig. 1 with the horn support and cover plate removed.

Fig. 4 is a view looking at the pole ends of the magnet taken on the line 4—4 Fig. 1.

Fig. 5 is a partial sectional view taken on the line 5—5 Fig. 4.

Fig. 6 is a plan view of the cover for the operating parts, and Fig. 7 is a plan view of the lower half of the magnet with the armature and coil in place.

As shown in the drawings 1 is a ring of T section into one face of which is fitted the cover plate 2, and in the opposite face is fitted the circular spider plate 3. The cover plate 2 and the circular spider plate 3 are held firmly in place in the ring 1 by means of the screws 4. Securely fastened to the circular spider plate 3 by means of the screw 5 are the upper and lower halves of the permanent magnet 6 and 7 respectively. Located in U shaped slots machined in the pole ends of the upper and lower halves of the magnet 6 and 7 is the coil 8 comprising the fine wire 9 tightly wound upon the spool 10. The coil 8 is prevented from moving endwise by the lugs 11 located on the outer faces of the side flanges of the spool 10.

Flexibly mounted in the core of the spool 10, and centrally located is the armature 12 to the inner end of which is securely fastened the connecting link 13 which passes through the hole 14 in the lower half 7 of the magnet, and the hole 15 centrally located in the circular spider plate 3 for that purpose. (See Fig. 5.) The diaphragm 16 is firmly fastened to the connecting link 13 by means of the shouldered portion thereof and the screw 17. The periphery of the diaphragm 16 is firmly held against lateral movement by the tubular rubber rings 18 which are compressed against it by the cover

plate 2 and the circular spider plate 3. (See Fig. 1.)

The coil 8 is connected to the binding posts 19 located in two of the arms of the circular spider plate 3, by the leads 20 attached to the binding post connections 21 which are held in position by the check nuts 22. The line leads 23 leading from the receiving circuit not shown are connected 10 to suitable binding post connections 24 which are held in position on the binding posts 19 by the lock washers 25 and check units 26. The binding posts 19 are insulated from the circular spider plate 3 by 15 means of the conical insulating plugs 27 and the insulating plates 28 which also insulate the binding post connections 21 from said circular spider plate 3. (See Fig. 1.) The insulating plates 28 are of such shape 20 and size to allow for their being used as guides for centrally locating the magnet as is most clearly shown in Figures 2 and 4.

The metal cover 29, enclosing the operating parts is fastened to the circular spider plate 3 by the screws 30. In the side wall 25 of said cover is an opening or hole 31 through which pass the line leads 23 (Figures 1, 2 and 5). The top of the cover 29 has a series of holes 32 punched therein, 30 which may be arranged in a circle as shown in Fig. 6, which are covered by a very fine wire mesh 33, held in position by the wire ring 34 which is soldered in position. The purpose of these holes 32 is to allow air to 35 pass in or out of chamber formed by the cover 29 and the circular spider plate 3 when the diaphragm 16 vibrates. The purpose of the fine wire mesh 33 is to prevent particles of dirt or dust from entering the chamber 40 which in time would be a great hinderance to the operation of the receiver.

The cover plate 2 has integral therewith and centrally located, the slotted collar 35 for the reception of a horn, an ear-tube or the like not shown in the drawings, and held securely therein by the binding screw 45 36.

In accordance with the provisions of the patent statutes, I have described the principle of my invention together with the apparatus which I now consider to represent a practical embodiment thereof, but I desire it understood that my invention is not confined to the particular form of apparatus 50 herein shown and described, the same being merely illustrative, and that the invention can be carried out in other ways without departing from the spirit of my invention, 55

and, therefore, I claim broadly the right to employ all equivalent instrumentalities 60 coming within the scope of the appended claims, and by means of which objects of my invention are attained, and the new results accomplished, as herein set forth, as it is obvious that the particular embodiment 65 herein shown and described is only one of many that can be employed to attain these objects and accomplish these results.

Having thus described my invention what I claim as new and desire to secure by Letters Patent is:—

1. In a device of the character described, a receiver of the telephone type, a coil, a permanent magnet comprising two halves and embracing said coil between its poles, a 75 flexible armature positioned within the core of said coil, a diaphragm, and a link, passing through one of the halves of said permanent magnet to connect said armature to said diaphragm.

2. In a device of the character described, a receiver of the telephone type, a coil, a permanent magnet comprising two halves held in position by one screw and embracing said coil between their poles, an armature flexibly mounted in the core of said coil, a diaphragm, and a link, passing through one of the halves of said permanent magnet, to connect said armature to said diaphragm.

3. In a device of the character described, a receiver of the telephone type, a coil, a permanent magnet having its poles slotted to embrace said coil, an armature flexibly mounted in the core and extending beyond 95 the sides of said coil, a connecting link rigidly fastened to one end of the armature and passing through one leg of said magnet, and a diaphragm rigidly connected to the other end of said connecting link.

4. A permanent magnet for telephone receivers comprising a pair of substantially similar, substantially rectangular bars, each having a pair of semi-cylindrical recesses in one of its sides and a depressed surface 105 adjacent one of its ends, said recesses being placed at right angles to each other, said bars, when secured together contiguously with the recesses of one opposite the corresponding recesses of the other, forming a 110 U-shaped magnet with a coil chamber adjacent its poles.

This specification signed this 29 day of April, 1925.

MORRIS M. GRUBER.
